UNITED STATES PATENT OFFICE.

JAMES M. SEYMOUR, JR., OF NEWARK, NEW JERSEY.

TORPEDO.

1,275,482.

Specification of Letters Patent. Patented Aug. 13, 1918.

Application filed June 2, 1917. Serial No. 172,403.

To all whom it may concern:

Be it known that I, JAMES M. SEYMOUR, Jr., a citizen of the United States, residing at Newark, in the county of Essex and State 5 of New Jersey, have invented certain new and useful Improvements in Torpedoes; and I do hereby declare the following to be a full, clear, and exact description of the invention, such as will enable others skilled in 10 the art to which it appertains to make and use the same, reference being had to the accompanying drawings, and to characters of reference marked thereon, which form a part of this specification.

15 The present invention has reference, generally, to an improved construction of torpedo; and the invention relates, more particularly, to a novel arrangement and construction of dirigible torpedo provided with 20 a self-contained power plant for propelling the same.

The invention has for its principal object to provide a dirigible torpedo having a surface float for supporting the same in a submerged condition, and the interior of said 25 torpedo having arranged therein, in a novel manner, a propelling hydrocarbon engine provided with means connected between the 30 torpedo hull and supporting float for supplying air to support the functioning of the said hydrocarbon engine.

Other objects of the present invention, not at this time more particularly enumerated, will be clearly understood from the following 35 detailed description of the same.

With the various objects of my present invention in view the same consists, primarily, in the novel construction of torpedo and self contained propelling power plant therefor 40 hereinafter set forth; and the invention consists, furthermore, in the several novel arrangements and combinations of the various devices and parts, as well as in the details of the construction of the same, all of which 45 will be more fully described in the following specification, and then finally embodied in the claims which are appended to and which form an essential part of said specification.

The invention is clearly illustrated in the 50 accompanying drawings, in which:—

Figure 1 is a part side elevation and part longitudinal section of my novel torpedo illustrating the internal arrangement of the self contained propelling power plant therefor; Fig. 2 is a horizontal section taken on line 2—2 in said Fig. 1, drawn on an en-

larged scale; Fig. 3 is a vertical longitudinal section of the water extractor of the air supplying means, also drawn on an enlarged scale; and Fig. 4 is a detail longitudinal section of a slightly modified construction and arrangement of air intake connected with the surface float of the torpedo.

Similar characters of reference are employed in all of the hereinabove described views, to indicate corresponding parts.

Referring now to the said drawings, the reference character 1 indicates the complete torpedo, the same being generally of the same dirigible type as is disclosed in my co-pending application for dirigible torpedo filed May 19th, 1917, under Serial Number 169,615/15. Said torpedo comprises a hull 2, preferably of the elongated cigar shape illustrated, and providing within its interior 75 housing for the several operating apparatus for driving and controlling the same, and for firing the explosive charge carried by the same. The reference character 3 indicates a suitable surface float or buoyant body 80 for supporting said hull in submerged condition. Said float 3 is operatively connected with the hull 2 by means of hanger-members 4 and 5, which are respectively riveted, or otherwise suitably secured, to the hull at the 85 bow end and forward of the stern end thereof, and which are respectively riveted, or otherwise suitably secured by their upper ends to the bow and abaft the midships portion of the float 3. Said hanger-members 90 are preferably constructed of steel, and incline rearwardly so as to permit the nose or bow of the torpedo to project beyond the bow of the float 3. The hanger-member 5, that is the stern hanger-member, is made in 95 hollow tubular form so as to provide an air conduit 6 within the same, the lower end of which extends into the interior of the hull 2, and the purpose of which will be presently disclosed. The upper end of said hanger 100 member 5 preferably extends upwardly through the interior of surface float 3 to the deck of the latter. Said surface float 3 is provided upon its deck with an upwardly projecting hollow or tubular funnel member 105 or mast 7, which is triangular in cross-section, so as to present its apex forward, whereby the same cuts the wind, and offers as little wind resistance to the forward movement of the float and hull as possible. The 110 back wall 8 of said hollow or tubular funnel member or mast 7 is provided, adjacent to its

- upper end, with a plurality of perforations 9 which afford air intakes into the interior conduit 10 of said funnel member or mast. Said upper end of said funnel member or mast is further provided with rearwardly projecting flanges 11, preferably flared outward, which are adapted to protect the air intakes, more or less, against the entrance of water, from spray or waves, therethrough.
- 10 The conduit 10 provided by said funnel member or mast 7 is so mounted and arranged that its lower end is connected in communication with the upper end of the conduit 6 provided by said hanger member 5.

Suitably arranged and located within the interior of said hull 2 is a hydrocarbon or gasoline internal combustion engine 12, which may be of any desirable type, and 20 which is arranged to provide power for driving the shaft 13 to which the torpedo propeller 14 is connected. Connected with said engine fuel manifold 15 is a carbureter 16, which may also be of any well known 25 or desired construction. The reference character 17 indicates a fuel or gasoline supply or storage tank, which is suitably connected by piping 18 to the carbureter 16.

Of course, it will be understood that the 30 practical use of the hydrocarbon engine as the propelling power plant of my submerged dirigible torpedo, depends entirely upon and is only rendered of possible use, by the provision of adequate means for supplying to the carbureter thereof unlimited 35 quantities of atmospheric air substantially free from water. To this end I have provided means whereby atmospheric air may be taken above water level of the surface 40 float and delivered to the carbureter 16 within the submerged hull 2 of the torpedo. A part of this air supplying means I have already described, to wit, the funnel member or mast 7 and the hanger-member 5 interconnected therewith. Since the conduit 45 6 of the hanger-member communicates with the interior of the hull 2, it will be apparent that any suitable means may be used to connect such conduit 6 with the air intake of carbureter 16, either directly or indirectly, so that a sufficient quantity of atmospheric air is readily supplied for mixture with gasoline to supply the combustible fuel for driving the engine 12. Since, however, 50 there is always more or less danger of some water finding its way into and through the air delivery conduits 10 and 6, I prefer to interpose between the inner end of the conduit 6 and the carbureter 16 an 55 extractor mechanism whereby any such water may be extracted or removed, so as not to be carried with the atmospheric air to the carbureter 16, to the detriment of the proper functioning of the latter in producing 60 a proper fuel mixture, and the conse-

quent interference with the proper operation of the engine 12. This extractor member comprises preferably a closed hollow drum 19 having a conical bottom 20, to which is connected the intake conduit 21 of a pump 22, of the rotary type shown, or of any other suitable type. Said drum 19 is further provided at one side with a tangential air intake or nozzle member 23, which is connected directly with the discharge end of the conduit 6 so as to receive the air therefrom, and then deliver the same tangentially into the interior of said drum 19. The air thus entering said drum 19 is given a swirling movement therein, and its exit from said drum is thereby delayed so that any water in the form of drops, etc., entering with the air may be separated by the centrifugal force and, under the force of gravitation, tend to drop into the cone shaped bottom 20 of said drum and there to accumulate. Connected with the upper or top wall of closure 24 of said drum is an air outlet 25, with which is connected the conduit or pipe 26 leading to the air intake of the carbureter 16, so that the air freed of water is drawn from the upper end of said drum to the carbureter, and then mixed with gasoline within the latter to form a proper combustible fuel or mixture supplied by the carbureter to the engine according to its needs.

Any water accumulated within the cone shaped bottom of the drum 19 is drawn off by the pump 22, and discharged outboard 100 through the discharge pipe 27 into the sea by the operation of said pump. Said discharge pipe 27 is also provided with a check-valve 28 of suitable construction, so that sea water is prevented from backing 105 up through the same and the pump. It will also be understood that the pump may be driven from the engine, or otherwise, by suitable transmission mechanism.

From the above description it will be readily apparent that my present invention provides a novel and practical means for supplying air to an internal combustion engine located within and driving a submerged or sub-surface torpedo, thus rendering it possible to utilize the comparatively cheap and powerful prime mover afforded by such an engine, under the unusual conditions resulting from its location within a subsurface or submerged hull.

Of course, various changes may be made in the arrangement and construction of the air conduits, as the same are related to the torpedo hull and the surface float, consequently I do not desire to limit myself exclusively to the arrangement above described. As a further example of such air conduit arrangement, I have illustrated a modification thereof in Fig. 4 of the drawings. In this construction, I do away with

the funnel member or mast 7, and provide the stern deck of my surface float 3 with a plurality of air intake perforations 29 which lead directly into an air collecting 5 compartment 30 in the stern of said surface float. Said compartment 30 may be connected by a suitably formed conduit 31 with the upper end of said conduit 6, so that the air may flow from said compartment 30 10 through said conduit 6 directly to the apparatus within the torpedo hull 2.

It will also be understood that the atmospheric air is drawn through the delivery conduits, extractor, and carbureter by the 15 suction produced by the engine 12, when operating, in the usual manner.

The exhaust from the engine 12 is conveyed through an exhaust pipe 32 which emerges from the hull 2, and which extends 20 aft to a point above and astern the propeller 14, so that the breaking up of the water by bubbles of exhaust gas ejected from the engine takes place astern the propeller, and consequently does not disturb the water in 25 which the propeller is rotating, so as to interfere or render ineffective the thrust of the propeller.

I am aware that some changes may be made in the several arrangements and combinations of the various devices and parts of my above described invention, as well as in the details of the construction of the same, without departing from the scope of my invention as defined in the following claims. 30 Hence, I do not limit my invention to the exact arrangements and combinations of the various parts as described in the foregoing specification, nor do I confine myself to the exact construction of the details thereof as 35 illustrated in the accompanying drawings.

Copies of this patent may be obtained for five cents each, by addressing the "Commissioner of Patents, Washington, D. C."

I claim:

1. In a submerged torpedo, a hydrocarbon engine for propelling the same, a fuel supply for said engine, means projecting above the water level for admitting air into 45 said torpedo, a carbureter for mixing said fuel and said air for delivery to said engine, and means connected in mutual communication between said air admission means and said carbureter for separating water which 50 may accompany the air through said air admission means.

2. In a submerged torpedo, a hydrocarbon engine for propelling the same, a fuel supply for said engine, means projecting above 55 the water level for admitting air into said torpedo, a carbureter for mixing said fuel and said air for delivery to said engine, means connected in mutual communication between said air admission means and said carbureter for separating water which may 60 accompany the air through said air admission means, comprising a cylindrical drum having a conical bottom, an air nozzle communicating with said air admission means 65 and adapted to enter the side of said drum tangentially, a pump connected with the conical bottom of said drum, a discharge-pipe connected with said pump and projecting externally of said torpedo, a check-valve in said discharge-pipe, and an air supply pipe leading out of the top of said 70 drum to the air intake of said carbureter.

In testimony that I claim the invention set forth above I have hereunto set my hand 75 this 31st day of May, 1917.
